UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

METHOD OF MAKING BICYCLE CRANK-HANGERS.

1,165,316.

Specification of Letters Patent. Patented Dec. 21, 1915.

Application filed July 26, 1912. Serial No. 711,663.

To all whom it may concern:

Be it known that I, HJALMAR G. CARLSON, a citizen of the United States, residing at Worcester, in the county of Worcester and 5 Commonwealth of Massachusetts, have invented a new and useful Improvement in Methods of Making Bicycle Crank-Hangers, of which the following is a specification.

My invention relates to crank hangers arranged to contain the crank and crank bearing of a bicycle and which are supported by the frame of the bicycle, and it consists of an improved method of constructing the hanger from a single piece of metal with 15 fastening lugs integral with the same.

The objects of my invention are to reduce the cost of manufacture and to secure accuracy of shape, which I attain by the method hereinafter described and illustrated in the 20 accompanying drawings, in which—

Figure 1 is a plan view of the blank from which the hanger is constructed. Fig. 2 is an edge view of the same. Fig. 3 is a side view of the punch by which the first step in 25 the construction of my hanger is accomplished. Fig. 4 is an edge view of the blank after being subjected to the action of the punch shown in Fig. 3. Fig. 5 is a side view of the die employed in connection with 30 the punch shown in Fig. 3. Fig. 6 is a side view of the punch used in the second step of my method. Fig. 7 is an edge view of the blank after being subjected to the action of the punch shown in Fig. 6. Fig. 8 is a plan 35 view of the same. Fig. 9 is an edge view of the blank after the flanges 15 have been formed thereon, and Fig. 10 is a perspective view of the completed hanger.

Similar reference characters refer to similar parts in the different figures.

Starting with a blank 1 of the shape shown in Figs. 1 and 2 and having holes 2, 2 and 3, 3 punched in the same, I subject the blank 1 to the action of a punch 4 and 45 a die 5, shown in Figs. 3 and 5, by which it is formed in the shape of the blank 6 shown in Fig. 4, with its opposite ends turned upwardly at 7, 7 and having a pair of recessed lugs 8 formed in its ends by the curved sections 9 of the punch 4. Leaving the blank 6 in the die 5 I apply to it the punch 10, 50 shown in Fig. 6, which is the same as the punch 4 shown in Fig. 3, except that shoul-

ders 11 extend around the curved portions 9 of the punch 10, by means of which the 55 upper irregular edges 12 of the lugs 8 formed on the blank 6 by the first punch 4 are upset and straightened, as shown at 13, 13 in Fig. 7, which represents the blank in edge view, and in Fig. 8 which shows the 60 blank in top view.

After the blank is shaped as shown in Figs. 7 and 8, flanges 15 are formed around the openings 2, 2 and 3, 3, Fig. 9, by suitable punches and dies. The blank is then bent 65 into a circular form with the lugs 8 abutting, as shown in Fig. 10. Holes 16 are bored directly through each pair of lugs 8 to secure a bolt inserted therein to draw the edges 13 of the lugs 8 toward each other. 70 Short pieces of pipe 17 are inserted in the openings 2, 2 and 3, 3 to which the frame of the bicycle is attached in a manner employed at the present time.

The hanger when constructed in accordance with my improved method is shown in perspective view in Fig. 10, and does not differ essentially from the hangers now in common use. By the method of manufacture as at present practised, however, the 75 hanger is formed from a piece of circular pipe, the lugs are formed therein or are attached thereto, and the pipe is then cut apart to enable the crank bearing to be 80 pinched therein.

By my improved method I form the hanger from a flat blank and shape the lugs before the blank is pressed into circular form. The cost of construction is thereby 85 greatly diminished, and the accurate shape 90 of the lugs and true circular shape of the hanger secured.

I claim,

The herein described method of making a bicycle crank hanger, comprising the stamping of recessed lugs on the ends of a flat blank or plate, the upsetting of the top edges of said lugs, and the bending of said blank into circular form to bring the edges 95 of lugs at opposite ends of the blank into engagement, as and for the purpose specified.

Dated this 22nd day of July 1912.

HJALMAR G. CARLSON.
